CABINET DOOR HANDLE

Harold P. Spehar, Detroit, Mich., assignor to American Motors Corporation, Detroit, Mich., a corporation of Maryland

Filed Oct. 23, 1965, Ser. No. 87,848

Term of patent 14 years

(Cl. D10—8)

FIGURE 1 is a perspective view of the cabinet door handle of my invention;

FIGURE 2 is a front elevational view of the cabinet door handle of FIGURE 1;

FIGURE 3 is a side elevational view showing the right side of the cabinet door handle of FIGURE 2;

FIGURE 4 is a side elevational view showing the left side of the cabinet door handle of FIGURE 2;

FIGURE 5 is a fragmentary rear elevational view of the cabinet door handle of FIGURE 2, the portion broken away being for convenience of illustration and is in appearance similar to the section adjacent thereto;

FIGURE 6 is a bottom plan view of the cabinet door handle of FIGURE 2;

FIGURE 7 is a cross section along line 7—7 in FIGURE 4; and

FIGURE 8 is a cross section along line 8—8 in FIGURE 2.

I claim:

The ornamental design for a cabinet door handle, substantially as shown.
